US00D816439S

(12) **United States Design Patent** (10) **Patent No.:** **US D816,439 S**
(45) **Date of Patent:** **** May 1, 2018**

(54) **IRRIGATION SPIKE**

(71) Applicant: **Steel Table Group LLC**, North Kansas City, MO (US)

(72) Inventors: **Dale J. Crook**, Olathe, KS (US); **Richard G. Brull**, North Kansas City, MO (US); **Robert M. Coulston**, Kansas City, MO (US); **Brian A. Hager**, Lenexa, KS (US); **Curtis R. McMillan**, Kansas City, MO (US); **Stanton W. Fernald**, Gardner, KS (US)

(73) Assignee: **Steel Table Group LLC**, North Kansas City, MO (US)

(**) Term: **15 Years**

(21) Appl. No.: **29/590,307**

(22) Filed: **Jan. 9, 2017**

Related U.S. Application Data

(63) Continuation-in-part of application No. 14/588,125, filed on Dec. 31, 2014.

(57) **CLAIM**

The ornamental design for an irrigation spike, as shown and described.

DESCRIPTION

FIG. 1 is a perspective view of an irrigation spike showing our new design;

FIG. 2 is a side elevational view of thereof.

FIG. 3 is a top plan view thereof.

FIG. 4 is a front elevational view thereof.

FIG. 5 is a bottom plan view thereof.

FIG. 6 is a perspective view thereof shown in a typical environment including a garden hose;

FIG. 7 is a side elevational view thereof; and,

FIG. 8 is a front elevational view thereof.

The broken line showing of a garden hose in FIGS. 6-8 is included for the purpose of illustrating and forms no part of the claimed design.

1 Claim, 8 Drawing Sheets
